2 SHEETS—SHEET 2.

UNITED STATES PATENT OFFICE.

JAMES W. WALLS, OF KANSAS CITY, MISSOURI.

SWITCH OPERATING AND LOCKING MECHANISM.

1,306,567.

Specification of Letters Patent. Patented June 10, 1919.

Application filed January 3, 1918. Serial No. 210,174.

To all whom it may concern:

Be it known that I, JAMES W. WALLS, a citizen of the United States, residing at Kansas City, in the county of Jackson and 5 State of Missouri, have invented certain new and useful Improvements in Switch Operating and Locking Mechanism, of which the following is a specification, reference being had therein to the accompanying drawing.

10 This invention relates to railroad switches and more particularly to mechanism for operating the swing rails and locking bolts, the object being to provide a switch operating and locking mechanism which is so constructed that the same can be readily operated from a switch stand or tower.

Another object of my invention is to provide mechanism which is exceedingly simple and cheap in construction, the parts thereof 20 being adjustably connected together and so mounted that a slight movement of the main switch operating rod and main lock operating rod will adjust the switch rails and locking bolts.

25 Other and further objects and advantages of the invention will be hereinafter set forth and the novel features thereof defined by the appended claims.

In the accompanying drawings,

30 Figure 1 is a plan view showing the application of my invention;

Fig. 2 is a perspective view of a portion of the switch operating rock shaft and lock operating rock shaft showing the manner of connecting the main operating rods thereto;

35 Fig. 3 is a perspective view of one of the lock bolt operating shafts showing the manner of connecting the same to the main rock shaft; and

40 Fig. 4 is a perspective view of one of the bearings and its connection with the rods for moving the stub rail.

Like numerals of reference refer to like parts in the several figures of the drawing.

45 In the drawing 1 and 2 indicate the rails of the main track, 3 and 4 the rails of the switch track, the main rail 2 and the switch rail 3 being formed with a gap at the junction thereof and the ends being mounted on 50 a base plate 5 and secured by the ordinary fastening means, said base plate being secured to the ties by spikes. The converging ends of these rails are connected by spacing blocks 6 and 7 provided with bolt openings 55 as shown in dotted lines through which the

locking bolts extend as will be hereinafter fully described.

Pivotedly mounted on the base plate 5 is a stub rail 8 capable of being swung to connect the ends of the rails. The main rails 1 60 and 2 are provided with gaps at their intersection with the switch rails 3 and 4, the ends thereof being mounted on plates 9 and 10 spiked to the ties. Mounted on these plates between the gaps formed in the main 65 rails are swing rails 11 and 12 adapted to be moved so as to register with the switch rails or main rails, the intersecting portion of the switch rail and main rail being connected together by spacing blocks 13 and 14 which 70 are provided with openings to receive locking bolts as will be hereinafter fully described.

In constructing the round bed for the switch some of the ties are extended and 75 thereon mounted blocks 15 provided with bearings 16 in which are pivotedly mounted main rock shafts 17 and 18. The rock shaft 17 at one end carries a crank arm 19 pivotally mounted in a knuckle 20, the internally threaded sleeve of which is adjustably mounted on the threaded end 21 of a flat switch operating rod 22 which is arranged under the plates 9 and 10 and is connected to the swing rails 11 and 12 by bolts 23 which 85 extend through the slots formed in the plates not shown so that when the main switch operating rod 22 is reciprocated the shaft 17 is rocked and the swing rails shifted. The opposite end of the main switch operating rod 22 is threaded as shown at 24 and carries a knuckle 25 which is connected to the crank of a switch stand 26.

Secured to the rock shaft 18 is a bifurcated crank 27 to which is pivotedly connected a knuckle 28 by a link, said knuckle being mounted on the threaded end of the main lock operating rod 29 extending parallel to the main operating rod 22 and provided with a knuckle 30 which is connected 95 to a crank arm of the switch stand 26. In the drawings I have shown a switch stand constructed in the ordinary manner by means of which the lock operating rod is operated prior to the switch operating rod, 100 and I do not wish to limit myself to any particular construction of switch stand as these operating rods can be connected through suitable mechanism, to operating means arranged in a tower.

In order to provide means for swinging the stub rail 8 simultaneously with the swinging of the swing rails 11 and 12, I provide the rock shaft 17 with spaced crank 5 arms 31 and 32 in which are mounted knuckles 36 and 37, provided with internally threaded tubular sleeves adjustably mounted in the threaded ends of rods 38 and 39, the rod 39 extending under the base 10 plate 5 and carrying a bolt extending at right angles thereto adapted to pass through a slot formed in the base plate and to be connected to the stub as shown at 40.

The rod 38 at its opposite end to its connection 15 with the rock shaft 17 has threads on which is adjustably mounted the threaded sleeve of a knuckle 41 which is pivotally connected to one of the arms of a lever 42 mounted on a bearing 43. The opposite end 20 of the lever 43 has secured there a knuckle 44 adjustably secured on a rod 45 which is also provided with a bolt extending at right angles thereto to which is connected the opposite end of the stub rail 8 as shown at 46, 25 said bolt passing through a slot in the base plate 5.

From the construction thus far described it will be seen that I have provided means for swinging the stub and swing rails by 30 rods operated by a rock shaft in such a manner that a slight movement of the rock shaft is sufficient to operate the swing rails of the switch.

Secured to the rock shaft 18 are crank 35 arms 47, 48, and 49 provided with bifurcated ends in which are mounted twisted links 50 having their opposite ends mounted in knuckles 60 which are provided with internally threaded sleeve portions mounted 40 on the threaded angled ends of lock bolt operating rock shafts 61, 62 and 63, said shafts being mounted in bearings 64 carried by blocks 65 secured to the ties. The shaft 61 is provided with spaced crank arms 66 to 45 which are connected knuckles 67 carrying tapered lock bolts 68, the ends of which are threaded into the internally threaded sleeves of the knuckles so that the same can be adjusted. These lock bolts 68 extend through 50 the openings in the spacing blocks 13 and 14 and coöperate with the swing rails 11 and 12 so as to lock these rails in their adjusted positions.

The shaft 62 is provided with a crank 69 55 to which is connected a knuckle 70 carrying a lock bolt 71 extending through the opening of the spacing block 7 and adapted to engage one end of the stub rail 8. The shaft 63 is provided with a crank arm 72 60 carrying a knuckle 73 which is provided with a threaded stem in which the threaded end of a lock bolt 74 is adjustably mounted, said lock bolt extending into the opening of the space block 6 and adapted to 65 engage the stub rail 8.

The construction of lock bolts are substantially the same and the manner of connecting the knuckles carrying the bolts to the operating shafts are the same as shown in Fig. 3.

From the foregoing description it will be seen that I have provided a switch operating and locking mechanism in which all of the parts carry adjustably connecting members so during the installing of the switch 70 the parts can be readily adjusted, and in Figs. 2, 3 and 4 I have shown details of construction of several parts all the other parts corresponding with these parts, that is, each crank arm of the rock shaft 17 is 75 connected to the rods for operating the swing rail in substantially the same manner as the main operating rods are connected thereto as shown in Fig. 2.

One of the furcations of each of the bifurcated knuckles is provided with a threaded aperture into which extends the threaded end of a pivot pin 34 for securing the links 50 therein as clearly shown in Fig. 3.

I claim:

1. A swing rail switch operating and locking mechanism comprising a pair of main rock shafts adapted to be arranged to one side of said switch, a series of lock bolt operating rock shafts connected to one of the first mentioned rock shafts, lock bolts pivotally connected to said lock bolt operating shafts adapted to lock the movable switch rails, and a series of rods connected to the other main rock shaft having connections with the 95 100 swinging rails of said switch.

2. In a switch operating and locking mechanism, the combination with a pair of main rock shafts, a switch stand having operating and locking rods adjustably connected thereto, a series of lock bolt operating rock shafts adjustably connected to one of the first mentioned rock shafts, lock bolts pivotally connected to said lock bolt operating shafts adapted to lock the movable switch rails, 105 110 guide blocks for said bolts, and a series of rods adjustably connected to the other main rock shaft having connections with the swinging rails of said switch.

3. In a switch operating and locking mechanism, the combination with a pair of main rock shafts, each rock shaft having a series of crank arms secured thereto, switch operating rods connected to the crank arms of one of said rock shafts, lock bolt operating 120 125 rock shafts connected to the crank arms of the other main rock shaft, a switch stand for operating said rods, and a series of adjustable lock bolts pivotally connected to the lock bolt operating shafts.

4. A switch operating and locking mechanism, comprising a pair of main rock shafts, crank arms carried by each of said main rock shafts, switch operating rods adjustably connected to the crank arms of one of 130 135

- said shafts, a series of rock shafts arranged at right angles to the first mentioned rock shafts, means for connecting said last mentioned rock shafts to the cranks of one of the first mentioned rock shafts, said rock shafts carrying locking bolts for locking the movable rail of the switch in adjusted position, and guide blocks for said bolts.
5. A switch operating and locking mechanism comprising a pair of spaced main rock shafts, one of said rock shafts having a series of switch operating rods pivotally connected thereto, a series of lock bolt operating shafts pivotally connected to the other main rock shaft, said lock bolt rock shafts being provided with cranks, knuckles pivotally mounted on said cranks, and lock bolts adjustably carried by said knuckles.
10. A switch operating and locking mechanism comprising a pair of main rock shafts, arranged to one side of the switch, a switch stand for independently rocking said shafts, cranks fixed on said rock shafts, switch operating rods connected to the cranks of one of said rock shafts, and rock shafts adjustably connected to the cranks of the other main rock shaft, said last mentioned rock shafts carrying lock bolts.
15. A switch operating and locking mechanism comprising a pair of main rock shafts, one of said rock shafts having a connection with said first mentioned rock shafts, and a series of rods adjustably connected to the other main rock shaft connected to said movable switch rails, and a switch stand for operating the main rock shafts.
20. A switch operating and locking mechanism comprising a series of plates, each plate having bearings, spaced rock shafts
25. A switch operating and locking mechanism, comprising a series of plates, each plate having bearings, spaced rock shafts
30. A switch operating and locking mechanism comprising a series of plates, each plate having bearings, spaced rock shafts
35. A switch operating and locking mechanism comprising a series of plates, each plate having bearings, spaced rock shafts
40. A switch operating and locking mechanism comprising a series of plates, each plate having bearings, spaced rock shafts
45. A switch operating and locking mechanism comprising a series of plates, each plate having bearings, spaced rock shafts
50. A switch operating and locking mechanism comprising a series of plates, each plate having bearings, spaced rock shafts
55. A switch operating and locking mechanism comprising a series of plates, each plate having bearings, spaced rock shafts

In testimony whereof I hereunto affix my signature in the presence of two witnesses.

JAMES W. WALLS.
